GEORGE KARRMANN, OF ANSONIA, ASSIGNOR TO HIMSELF AND CHARLES ALVORD, OF WOLCOTTVILLE, CONNECTICUT.

Letters Patent No. 96,011, dated October 19, 1869.

IMPROVED MACHINE FOR MAKING NEEDLES FOR SEWING-MACHINES.

The Schedule referred to in these Letters Patent and making part of the same.

To all whom it may concern:

Be it known that I, GEORGE KARRMANN, of Ansonia, in the county of New Haven, and State of Connecticut, have invented and made a new and useful Improvement in Machinery for Making Needles; and I do hereby declare the following to be a full, clear, and exact description of the said invention, reference being had to the annexed drawing, making part of this specification, wherein—

Figure 1 is a plan of the machine.

Figure 2 is a cross-section of the same, at the line $x\ x$.

Figure 3 represents the needle, with its hooked point in the form produced in this machine, the same being in enlarged size.

Similar marks of reference denote the same parts.

The object of this machine is to produce needles with hooked points, such as are employed in sewing boots and shoes by machinery, crochet-work, &c.

To produce the most perfect hook, it is necessary that the throat of the hook, over which the cord or thread lies, shall be a semicircular groove, free from roughness, in order that the thread may not be injured by being drawn by said hook, or while sliding through the same.

I accomplish this by clamping the needle-blank to a turn-table, and employ a revolving tool, that is brought up to an adjustable stop, and acts to cut away the metal to form the throat of the hook, while the blank is revolved with the turn-table, about an axis, which coincides with the centre of the semicircular groove forming the bottom of the throat of the needle.

The surplus metal at the sides and point of the needle-blank is removed by cutters that act separately from the said throat-tool.

In the drawing—

a is a table or bed, upon which is mounted the turn-table b , that is fitted with teeth around its periphery, so that it can be given a half rotation, or nearly so, by the segmental gear c and lever d .

This gear c is on a fulcrum-stud or gudgeon, 2, and a sector, c' , with a cord or chain over the pulley 3, to a spring, 4, or weight, is employed to return the parts to a normal position, and hold them.

Between the turn-table b and its base, on the bed a , stops are applied to the respective parts, so that the turn-table can only receive the proper amount of rotation, which, with most characters of hooked needles, will be about one-half a revolution.

Upon this turn-table b is the needle-holder, formed of a standard, b' , upon the top of which is the clip e , that comes over the needle i , and on the side of b' is a clamping-plate, g , that serves as a support for the needle-blank, and as a clamp to hold the needle firmly against the side of the standard b' , and the under side

of the clip e , the upper edge of this clamping-plate g being slightly bevelled for this purpose.

A screw passes through this plate g , into the standard b' , and a standing screw-driver or wrench, h , supported by an arm, h' , engages with this screw when the parts are at rest, so that the clamp g can be loosened, and another needle-blank inserted, after the previously partially-finished blank is removed.

A stop, k , is provided to indicate the position of the end of the blank.

It will be seen, that the axis of the needle-blank intersects and crosses the vertical axis of the turn-table b , and this point of intersection forms the centre, around which the groove at the bottom of the hook is formed.

The frame l is mounted on the standard m , and is actuated by the strap or cord n , and treadle n' , and returned or lifted by the spring or weight o , acting upon a cord over the sector o' .

The frame l carries a slide, p , that is adjustable in l , and on this slide p are the bearings for the shaft q , driven by competent power; and q' is a wheel on the shaft q , taking the gears 13 and 14 of the shafts r & s , upon the ends of which are the cutter-wheels r' and s' .

The boxes or bearings of these shafts may be adjustable.

The cutter r' is of a V-shape, so as to cut across the end of the needle, and leave the same with a chisel-shaped or double-inclined point, to be afterwards finished by hand, upon a wheel, or otherwise.

The cutter s' is double, and is operative in cutting away the metal at the sides of the hook, leaving a rib that is afterward under-cut, to produce said hook.

A screw-stop, 5 , on the turn-table b , regulates the distance that this cutter s' penetrates the side of the needle.

After the cutters r' s' have acted on the blank, and been raised up, the tool t is brought into action.

This tool t is mounted upon an arbor, u , in a sliding head-block, u' , and t' is a pulley, by which to apply power in rotating the tool t .

The lever v is connected to the sliding head-block u' at 9, and a link, v' , connects, from the end of the lever v , to the bed a .

A spring or weight, at 10, is employed to draw back the slide u' and tool, and a stop, 11, and adjustable screw, 12, regulate the point to which the tool can be projected, so as to come up properly to the needle-blank.

After the blank has been partially formed by the cutters r' s' , the sliding head-block u' and tool t are moved along by the lever v , and then the turn-table and needle-blank are given a gradual movement, while the tool t is cutting; and the shape of this tool t is

such as to form the necessary groove inside the hook, and cut out and shape the metal at the throat or opening of the hook, as seen in fig. 3.

By this construction of machine, the parts can be adjusted, so as to form a hook upon the needle-blank in the most perfect manner, and there will be but little finishing to be done by hand.

What I claim, and desire to secure by Letters Patent, is—

1. The combination of a clamp or blank-holder with the tools r' s' , arranged in respect to each other and to

the needle-blank, substantially as shown and described, and for the purposes set forth.

2. The combination of the tools r' s' and t with the rotary clamp b , all arranged and operating substantially in the manner and for the purposes set forth.

In witness whereof, I have hereunto set my signature, this 4th day of May, A. D. 1869.

GEORGE KARRMANN.
